UNITED STATES PATENT OFFICE.

JAMES MACAULAY, OF LYNN, MASSACHUSETTS.

LIFE-PRESERVER.

1,138,495.

Specification of Letters Patent.

Patented May 4, 1915.

Application filed September 9, 1914. Serial No. 860,939.

To all whom it may concern:

Be it known that I, JAMES MACAULAY, a citizen of the United States, residing at Lynn, in the county of Essex, in the State of Massachusetts, have invented a certain new and useful Improvement in Life-Preservers, of which the following is a specification, reference being had to the accompanying drawings.

10 This improvement relates to the class of life preservers which include an inflatable belt or vest and my present purpose is to provide an extremely light, and reasonably cheap, preserver in which special provision is made for inflating the belt member either before or after the said belt has been placed in its operative position on a person; thus rendering it possible and feasible for the preserver to be worn deflated, under a vest 20 or waist, and to be inflated at a moment's notice whenever the belt is needed.

My invention is illustrated in the annexed drawings; Figure 1 being a perspective view of a life preserver embodying my said improvements, and Fig. 2 is a relatively enlarged front elevation of the meeting end portions of said preserver. Fig. 3 is a top or plan view of the device of Fig. 2. In Fig. 4 I have shown, detached, the air pump by 30 means of which the life preserver may be inflated and in Fig. 5 the said pump is shown partly in central longitudinal section in order to disclose the interior construction of said pump.

35 Referring to these drawings the letter *a* indicates an inflatable belt made preferably of waterproofed silk, or the like serviceable and light material, which may be rolled into a small package so that it may be easily carried in a hand-bag or pocket; said belt being provided, if desired, with shoulder straps. While the said belt may be an unbroken ring, I prefer to form it as seen in Fig. 1, and with snap-hooks *b*, or the like devices, where- 40 by the belt may be readily clasped around the body of the wearer; the otherwise cut and open ends of the preserver being tightly bound and stiffened by strips *c* of fiber or metal that are riveted upon the said ends. 45 Adjacent to one end of the described preserver is an air pump *d*, by means of which the belt may be inflated and adjacent to the other end of the preserver is a relief valve *e* by means of which the belt may be deflated. 50

55 The lower, or valve portion of the pump *d* is contained in section *d'* which is perma-

nently secured in the belt, by cementing or otherwise, said section *d'* being threaded internally to receive the externally threaded lower end of the pump *d*; this construction 60 being such that the said pump may be unscrewed and removed from the belt, if desired, after the belt has been inflated. With such removable feature in view, the pump is contained in a suitable sheath in the belt; the 65 valve section *d'* being permanently seated in the belt at the lower end of said sheath.

Referring now to Figs. 4 and 5 of the drawings, the barrel portion of the pump *d* is made of tubing and said pump includes a 70 piston *d⁴* carried by the otherwise free end of a rod, *f*, which is slidably mounted in the head *d²* of the pump and has a handle *d³* by means of which the pump may be operated.

The lower end of the pump barrel has an 75 opening *g*, whereby a connection is made between the pump chamber and the valve section *d'* when the pump and said valve section are screwed together. The upper part of the valve section is cupped and threaded 80 to receive the pump and the lower part of said valve section is chambered as at *h*, to receive disk *k* which is maintained in its uppermost position by a light spring *m*, in order to close normally port *n* in the wall be- 85 tween the chamber *h* and the cupped upper part of the valve section. The lower end of the valve section is also provided with a port or opening *o*, which connects chamber *h* with the interior of the belt *a*. 90

The letter *e* indicates a relief valve by means of which the air in belt *a* may be released so that said belt may be rolled up for storage or shipment.

When it is desired to use my described life 95 preserver, the belt *a* is placed around the body, under the arms. The handle *d³* is then grasped and the piston plunger *d⁴* is reciprocated in the barrel *d*, each stroke resulting in forcing air through the valve openings in 100 to the belt *a*; the valve disk *k* yielding at each stroke of the plunger to allow the entrance of the air and then closing to prevent the escape of the air, and this operation is repeated until the belt is sufficiently inflated. 105 The pump *d* may be unscrewed from the thimble and removed from the sheath or it may remain in said sheath for convenient use in the event that the air escapes from the belt by leakage or otherwise. 110

While my described device is specially valuable as a life preserver, it may also be used

with decided advantage when learning to swim, the belt being gradually deflated as the pupil acquires practice and confidence, and until said belt is no longer needed.

5. Having thus described my invention, I claim as new and wish to secure by Letters Patent:

In combination, in a life preserver, an in-

flatable belt, a sheath formed in said belt, a valve fixed in said sheath, and an air pump 10 located in said sheath and removably attached to said valve.

JAMES MACAULAY.
